(57) CLAIM

The ornamental design for a wireless telemetry unit, as shown and described.

DESCRIPTION

FIG. 1 is a pictorial view of a wireless telemetry unit in accordance with my invention, with the environment for mounting the unit being shown in dashed lines.

FIG. 2 is a top view of the unit shown in FIG. 1.

FIG. 3 is a bottom view of the unit shown in FIG. 1.

FIG. 4 is a left side view of the unit shown in FIG. 1.

FIG. 5 is a front view of the unit shown in FIG. 1.

FIG. 6 is a back view of the unit shown in FIG. 1.

FIG. 7 is a right side view of the unit shown in FIG. 1.

FIG. 8 is a pictorial view of the wireless telemetry unit in accordance with my invention, with the environment for mounting the unit being shown in dashed lines.

FIG. 9 is a top view of the unit shown in FIG. 8.

FIG. 10 is a bottom view of the unit shown in FIG. 8.

FIG. 11 is left side view of the unit shown in FIG. 8.

FIG. 12 is front view of the unit shown in FIG. 8.

FIG. 13 is a right side view of the unit shown in FIG. 8; and, FIG. 14 is a back view of the unit shown in FIG. 8.
